UNITED STATES PATENT OFFICE

2,477,333

RIBBON REEL MADE OF A SINGLE BLANK

William H. Hawkins, Stamford, Conn., assignor
to Freyberg Bros. Strauss, Inc., New York,
N. Y., a corporation of New York

Application May 8, 1946, Serial No. 668,070

3 Claims. (Cl. 206—51)

1

This invention relates to a packaging reel, and more particularly to a packaging reel of the type disclosed in my earlier Patent No. 2,368,594 dated January 30, 1945.

In that patent I disclose a reel having a central box-like member about which the ribbon is wound. Upon completion of the winding of the ribbon, flanges may be applied to the central box-like member, thereby completing the packaging of the ribbon. While the invention of my patent has enjoyed considerable success, I have found that it is desirable to form the packaging reel from a single blank, thereby avoiding the flange assembly operation of my patent. However, it has heretofore not been possible to form the flanges integrally with the ribbon supporting portion and extending beyond the ribbon at every point of the periphery of the resulting reel to protect the ribbon.

It is the object of the present invention to contribute to the art a packaging reel that may be assembled from a single blank, the assembly to be inexpensive, and to contribute a final completely flanged package that will be attractive and durable.

It is a further object of my invention to provide a packaging reel having portions for securing the end of the ribbon thereto at the beginning of a packaging operation, whereby to facilitate the winding of the ribbon on the reel.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized by those skilled in the art as a basis for the designing of other structures for carrying out the several purposes of my invention. It is important, therefore, that the claims to be granted me shall be of sufficient breadth to prevent the appropriation of my invention by those skilled in the art.

Referring now to the drawings, Fig. 1 is a perspective view of my packaging reel completely assembled. Fig. 2 is a side view of the completed reel while Fig. 3 is a view looking downwardly on the end of the reel of Fig. 2. Fig. 4 shows the single blank from which my packaging reel of Fig. 1 is formed.

Referring now more particularly to the draw-

ings, and especially Figs. 1 and 4, the blank from which my reel is formed is designated generally by the reference letter R. This blank comprises a finishing flange 10 and a finishing flange 11, each cut out at 12 for winding pins used to rotate the reel whereby to wind the ribbon thereon, all as is well set forth in my earlier patent.

The finishing flanges 10 and 11 are connected by what I term a ribbon supporting portion 13. 10 This ribbon supporting portion 13 is formed with a central part 14 and margins 15 and 16 to which adhesive material may be applied. Score lines are formed at 17 and 18 to facilitate the bending of the margins 15 and 16 relatively to the central part 14. Additional score lines 19 are formed to provide bending lines for tabs 20, these tabs being cut away from the margins 15 and 16 along lines 21.

Secured to the finishing flange 11 is a second 20 ribbon supporting member 25 having a central portion 26 and margins 27 and 28, the margin 28 being directly secured to the finishing flange 11. Margins 27 and 28 are adapted for covering with adhesive material in the same manner as margins 15 and 16. As is the case with ribbon support 13, the central part 26 is separated from the margins 27 and 28 by score lines 29 and 30. Similarly, tabs 31 are formed by the cutting of the ribbon supporting portions 25 along lines 32 and 30 by scoring along lines 33. The ribbon support 25, as a whole, is adapted for bending relatively to the finishing flange 11 along score line 34. Similarly, the first ribbon support portion 13 may be bent relatively to the finishing flanges 10, 11 by the scoring along lines 35 and 36.

In order to form the complete ribbon packaging reel of Fig. 1, blank R must be bent along the score lines described so that margin 16 will be caused to adhere to finishing flange 10 with the central part 14 of the ribbon support 13 extending at right angles from the finishing flange 10. The margin 15 of ribbon support 13 will then be secured by adhesive to the finishing flange 11 with the said finishing flange 11 lying parallel to the finishing flange 10. Margin 28 will then be secured adhesively to finishing flange 11 while the reel will be completed by the securing of margin 27 to the finishing flange 10. Tabs 20 and 31 will then be bent inwardly as best shown in Figs. 1 and 3 to provide supports for the ribbon, the ribbon being wound to lie on the said tabs and on the central portions 14 and 26 of the ribbon supports 13 and 25.

At this point it will be well to point out the fact that the finishing flanges overlie the ribbon

wound on the ribbon supports at every point. This furnishes protection to all parts of the ribbon as is so very important.

When beginning the winding operation through the utilization of the holes 12 of the finishing flanges, it is desirable to secure the end of the ribbon as those skilled in the art will appreciate. For the particular purpose, the central parts 14 and 26 of ribbon supporting portions 13 and 25 are slit to form a Y-shaped cut designated by the reference numeral 40. It is very simple to place a ribbon against one of the parts 14, 26 and force the end of the ribbon through the Y slit 40 so that it may be maintained yielding thereafter during the winding operation. Those skilled in the art will fully understand this portion of my invention. It is thought that the considerable utility and extremely desirable features of my invention will now be quite apparent.

I now claim:

1. A ribbon reel formed of a single blank having a pair of finishing flanges, a ribbon supporting portion between said flanges and spacing said flanges, said ribbon supporting portion having margins at each side thereof adapted for folding against the inside edge of each flange so as to locate the ribbon supporting portion inwardly of said flanges, a second similar ribbon supporting portion similarly extending from one of said flanges and adapted to be secured to the other of the flanges by means of one of its margins, said margins being narrow with relation to the flange widths whereby said two ribbon supporting portions are spaced from one another to form with the said flanges a hollow box-like structure, and a tab at each end of each ribbon supporting portion adapted for inward bending toward the other ribbon supporting portion for further support of the ribbon between said ribbon supporting portions.

2. A ribbon reel formed of a single blank having a pair of relatively long narrow finishing flanges, a relatively long narrow ribbon supporting portion between two of the long narrow sides of said flanges and spacing said flanges, said ribbon supporting portion having margins at each longitudinal side thereof adapted for folding against the inside longitudinal edge of each flange so as to locate the ribbon supporting por-

tion inwardly of said flanges, a second similar relatively long narrow ribbon supporting portion similarly extending from the longitudinal side of one of said flanges and adapted to be secured to the longitudinal side of the other of the flanges by means of one of its longitudinal margins, said margins being narrow with relation to the flange widths whereby said two ribbon supporting portions are spaced from one another to form with the said flanges a hollow box-like structure, and a tab at each end of each ribbon supporting portion adapted for inward bending toward the other ribbon supporting portion for further support of the ribbon between said ribbon supporting portions.

3. A ribbon reel formed of a single blank having a pair of finishing flanges, a ribbon supporting portion between said flanges and spacing said flanges, said ribbon supporting portion having margins at each side thereof adapted for folding against the inside edge of each flange so as to locate the ribbon supporting portion inwardly of said flanges, a second similar ribbon supporting portion similarly extending from one of said flanges and adapted to be secured to the other of the flanges by means of one of its margins, said margins being narrow with relation to the flange widths whereby said two ribbon supporting portions are spaced from one another to form with the said flanges a hollow box-like structure, and a tab at the end of at least one of said ribbon supporting portions adapted for inward bending toward the other ribbon supporting portion for further support of the ribbon between said ribbon supporting portions.

WILLIAM H. HAWKINS.
